UNITED STATES PATENT OFFICE.

C. FRED. LUQUER, OF MONTGOMERY, NEW YORK.

EIGHT-DAY-CLOCK ALARM.

SPECIFICATION forming part of Letters Patent No. 297,612, dated April 29, 1884.

Application filed August 15, 1883. (No model.)

To all whom it may concern:

Be it known that I, C. FRED. LUQUER, of 5
Montgomery, in the county of Orange and
State of New York, have invented a new and
Improved Eight-Day Alarm Attachment for
Clocks, of which the following is a full, clear,
and exact description.

Reference is to be had to the accompanying
drawings, forming part of this specification,
10 in which similar letters of reference indicate
corresponding parts in both the figures.

Figure 1 is a front elevation of my improve-
ment, part of the frame being removed, and
showing a part of the clock-dial. Fig. 2 is a
15 side elevation of the lower part of the same.

The object of this invention is to provide
alarm attachments for clocks constructed in
such a manner that they will sound an alarm
20 once each day for eight successive days with
one winding up of the spring, so that the
alarm mechanism will require to be wound up
only once a week.

The invention consists in an eight-day alarm
attachment for clocks, constructed with a dial
25 and cam connected with the clock-work, and
operating a lever connected by wires with an
arm attached to the pallet, and with a lever
arranged to engage with stop-pins attached to
30 the pallet-wheel, and provided with a follower
to engage with a trip-wheel connected with
the main wheel, driven by a spring, as will be
hereinafter fully described.

A represents the dial, and B the hands, of
an ordinary eight-day clock. C is the alarm-
35 dial. D is the cam. E is the drop-lever. F
is the pallet connecting-wire. G is the pallet-
arm. H is the pallet. I is the pallet-wheel.
J is the main wheel. K is the spring. L is
40 the bell-hammer, and M is the bell, all of which
parts are constructed and operate in the same
manner as in an ordinary alarm, except that
the spring K is made longer than is necessary
in a one-day alarm.

To the outer part of the side of the pallet-
45 wheel I are attached two pins, N, at a little
distance apart, and at the same distance from
the center of the said wheel. O is the stop-lever,
the forward end of which is widened, so that
50 it will engage with either of the stop-pins N.

The stop-lever O is pivoted to the frame P of

the alarm-work, and its rear end is connected
with the drop-lever E by the wire Q.

To the rear arm of the stop-lever O is at-
tached a pawl or follower, R, the free end of
which rests upon the rim of the trip-wheel S. 55
The trip-wheel S is rigidly connected with the
main wheel J, or its post, and has a notch or
re-entrant tooth, T, formed in its rim for the
follower R to drop into at each revolution of
the said wheel S. The forward side of the 60
notch T is square or radial, and its rear side
is inclined, so that the follower R will readily
pass out of the said notch as the trip-wheel
S continues its revolution.

In setting the mechanism, if the alarm is to 65
be sounded within twelve hours, the forward
end of the lever O must be arranged to rest
against the second pin N, which can be done
by moving the alarm-dial C, and the various
parts will then be in the following positions. 7c

The arm G is raised, causing the pallet H to
hold the wheel I from revolving, the rear end
of the lever O is raised, raising the follower R
from the notch T, and disengaging the forward
end of the said lever O from the second pin N. 75
With this arrangement, at the time for which
the alarm was set the end of the lever E drops
from the shoulder of the cam D, releasing the
pallet H and allowing the alarm to be sound-
ed. At the same time the follower R rides 80
along the rim of the wheel S until it reaches
and drops into the notch T, drawing the rear
arm of the lever O downward, and raising the
forward end of the said lever into such a pos-
ition that the first pin N will strike against it, 85
stopping the alarm-work, and holding it from
moving until the cam D has raised the lever E
and locked the pallet H, which movement has
also lowered the inner end of the lever O out of
engagement with the first pin N. At the end of 90
the next twelve hours the lever E again drops
from the shoulder of the cam D, which re-
leases the pallet H, and at the same time raises
the forward end of the lever O into the space
between the pins N, so that the said end will 95
be struck by the second pin N and the move-
ment stopped before the alarm has had time
to sound, and until the forward movement of
the cam D locks the pallet H, as before stated,
and releases the second pin N from the le. 100

ver O, the forward movement of the alarm- works from the action of the spring K, being enough in each case to cause the return of the forward end of the lever O to the rear of the 5 pin N, from the forward side of which it was last released. At the end of the next twelve hours, when the lever E drops from the shoulder of the cam D, the alarm mechanism is released, as before stated, and the alarm is sounded until the wheel J has made an entire revolution, and the forward end of the lever O is 10 again raised to meet the first pin N.

Having thus described my invention, I claim as new and desire to secure by Letters Patent—

15 1. An eight-day alarm attachment for clocks, constructed substantially as herein shown and described, and consisting of the dial and cam C D, the lever E, the connecting-wire, pallet-

arm, and pallet F G H, the connecting-wire Q, and the lever O, having follower R, the pallet-wheel I, having stop-pins N N, the main wheel J, having trip-wheel S, and the spring K, as set forth.

2. In an alarm attachment for clocks, the combination, with the drop-lever E, the pallet-wheel I, and the main wheel J, of the connecting-wire Q, the lever O, having follower R, the two pins N, and the trip-wheel S, having notch T, substantially as herein shown and described, whereby the alarm is made to sound 30 successively each day for a week with one winding of the alarm-spring, as set forth.
